AUTOMATICALLY EXPANDING MAIL RECEPTEACLES

Michael Firestone, Brooklyn, N. Y.

Application July 6, 1939, Serial No. 283,028

1 Claim. (Cl. 220—6)

My present invention relates to receptacles, and more particularly to the type adapted to be used to receive mail dropped through a slot in a door.

An object of this invention is to provide a receptacle of novel and improved construction which automatically expands as its contents are increased.

Another object hereof is to provide a novel and improved receptacle of the character mentioned, the capacity of which is variable and easily adjustable.

A further object is to provide a novel and improved receptacle for mail, which is unobtrusive in appearance, reasonably cheap to manufacture, simple in construction, easy to use and efficient in carrying out the purposes for which it was designed.

Other objects will become manifest as this disclosure proceeds.

20 In the accompanying drawing forming part of this application, similar characters of reference indicate corresponding parts in all the views.

Fig. 1 is a side view of an embodiment of the present invention.

25 Fig. 2 shows a plan thereof.

Fig. 3 is a perspective view showing the receptacle as mounted indoors onto a door, immediately below a mail slot.

30 Fig. 4 is a diagrammatic view of the receptacle in contracted condition.

Fig. 5 is a similar view showing the article in partially extended condition; interior components being omitted.

35 Fig. 6 is a view similar to that of Fig. 5, showing the receptacle in fully extended condition.

In the drawing, the numerals 15 and 16 designate open box halves, which are preferred so that they serve as the front and rear walls of the extended structure, and as all the walls of 40 the receptacle in its minimum contracted condition. These members 15 and 16, are associated in hinged relation respectively, with the hinged floor sections 17 and 18, in which set-up, the numerals 19, 20 and 21 indicate hinge lines.

45 Said floor sections have bent up tabs 22 at their side edges, so that pieces of mail 23 when lying on the sections 17 and 18, will be kept from slipping off. The numerals 24 and 25 indicate lazy tongs, preferably mounted to lie within the

50 box halves 15 and 16, up against the side wall portions 26. The assembly is maintained by means of headed pins or screws 27 extending from the lazy tongs through the slots 29 in wall portions 26.

55 It is intended that when the receptacle contract in capacity, that its floor shall fold so that sections 17 and 18 move upwardly therein. It is evident that the weight of matter thrown into

the receptacle through the mail slot 30 in the instance illustrated, will act to open the hinge 20, thereby causing expansion of the receptacle. The extent of such expansion is limited by any suitable stop means which in the embodiment shown is accomplished by the lug 31 extending from one of the box halves. The upper edge 32 of this lug slants upwardly towards the hinge line 20, so that when the receptacle is in fully extended condition, the floor sections 17 and 18, shall still be slanted upwardly toward their hinge line 20. When the article is mounted onto a door 33 by the suction cups 34 as an instance, or by any other suitable detachable or permanently mounting means, merely pushing or pulling the component 15, will alter the capacity of the receptacle and particularly contract the same so that its capacity is determined by the box formed by the components 15 and 16 when in contact. In this condition, lug 31 enters slot 35 to permit the formation of such small capacity box structure.

Normally, the article is in contracted condition. Then as a quantity of mail is thrown through the mail slot 30, the receptacle will automatically expand due to the action of the weight of such mail as hereinbefore explained, and then can be fed more mail matter to hold.

The teachings of this invention are capable of being embodied in numerous forms and adapted for various applications without departing from the essential features herein disclosed. It is therefore intended and desired that the embodiment set forth herein shall be deemed illustrative and not restrictive, and that the patent 30 shall cover whatever features of patentable novelty exist in the foregoing disclosure; reference being had to the following claim rather than to the specific description herein to indicate the scope of this invention.

40 I claim:

In a receptacle, front and rear walls; the rear wall being adapted to be mounted onto a support, extensible side walls comprising lazy tongs, interposed between the front and rear walls, and 45 supporting the front wall for substantially horizontal movement, and a bottom comprising hinged plates; said bottom being hinged at the front and rear walls; said plates when folded, lying in upwardly extending position between 50 said walls, whereby the weight of articles placed into the receptacle will cause the plates of the bottom to unfold, thereby automatically extending the side walls and means on one of said walls for preventing said plates from taking re- 55 spectively parallel positions when the receptacle is in fully extended condition.

MICHAEL FIRESTONE.
